UNITED STATES PATENT OFFICE.

GEORGE S. AUER, OF CLEVELAND, OHIO.

DESIGN FOR A WALL-REGISTER.

No. 40,038.

Specification for Design.

Patented June 8, 1909.

Application filed February 11, 1909. Serial No. 477,474. Term of patent 7 years.

To all whom it may concern:

Be it known that I, GEORGE S. AUER, a citizen of the United States, residing at Cleveland, in the county of Cuyahoga and State of Ohio, have invented a new, original, and ornamental Design for Wall-Registers, of which the following is a specification, reference being had to the accompanying drawing, forming part thereof.

The figure shows my newly designed wall register in perspective.

I claim:

The ornamental design for a wall register, as shown.

GEORGE S. AUER.
